L. A. BROWN

CLOTH HOLDING FRAME

Filed Jan. 15, 1926

Patented Jan. 4, 1927.

UNITED STATES PATENT OFFICE.

LUCIUS A. BROWN, OF CLAY CENTER, NEBRASKA.

CLOTH-HOLDING FRAME.

Application filed January 15, 1926. Serial No. 81,447.

This invention relates to an improved frame over which a weather-proof transparent cloth is stretched to form what may be termed a window.

5 This improved window has been especially designed with a view of supplanting the glass window now used to cover hotbeds in green houses and the like, but it is not to be restricted to this use for it is equally well 10 adaptable for use in poultry houses, and as a storm window for residences and the like.

For the purpose of convenience, the invention will be described for use in the plant grower's and gardener's art. It is now customary in this art to provide a frame which is covered with a transparent cloth frequently referred to as "glass cloth." This cloth is stretched over the frame during the winter, and in the spring it is removed and 20 put away in order to save it. Various methods have been employed for fastening the edges of the cloth to the bars of the frame for the purpose of stretching it tautly across the frame. In some instances single 25 fasteners such as nails and the like have been employed, and in other instances retaining cleats have been used. So far as I have been able to ascertain all present methods of fastening the cloth in place are such 30 that they permit the cloth to rot out, thus permitting it to be used for a single season, or making it necessary to cut off the frayed edges.

It follows that the primary aim in producing the present device has been to provide a novel means for connecting the cloth to the frame in a manner to permit it to be removed when desired, and to prevent rotting of the edges when in use. The novel 40 construction employed for accomplishing this result will be set out in detail in the following description.

In the accompanying drawing forming a part of this application and in which like numerals are employed to designate like parts throughout the same:

Figure 1 is a top plan view of a window or cloth frame constructed in accordance with this invention.

50 Figure 2 is a longitudinal section through the frame.

Figure 3 is a bottom plan view thereof, and

55 Figure 4 is a detail perspective view of one of the channel shaped cleats forming an important factor of the invention.

Referring to the drawings in detail, the reference character 1 designates generally a frame which embodies opposed longitudinal side bars 2, and end bars 3, the abutting edges of these being mitered as shown. Formed in the upper side of the frame is a marginal groove 4 which is spaced inwardly from the outer edges of the frame bars. At each corner is a vertical hole 5 extending 60 from the groove through the bottom of the frame, this hole constituting a drain duct as will be more clearly evident from the following description. As shown better in Figure 3 a central cross brace 6 is located 65 between the end bars to increase the rigidity of the structure. It will be observed from this figure that a pair of U-shaped clips 7 are fastened to the opposite ends of this brace and are provided with attaching 70 tongues 8, these tongues being fastened to the end bars of the frame. In this connection it is to be pointed out that in the ordinary window construction comparatively heavy 75 material is required in order to provide a 80 frame which will be sufficiently rigid to support the comparatively heavy glass ordinarily used. In the present arrangement however exceedingly light weight wood may 85 be employed and to permit this result to be better attained, metal cornices 9 are fastened to the under side of the frame and provided with upturned flanges fastened to the edges of the bars of the frame. It will 90 be noticed that these cornices are formed with openings 10 registering with the aforesaid drain ducts 5.

Stretched tautly over the top of the frame is a piece of substantially transparent weather-proof cloth 11. It is quite common 95 in the trade to refer to this well known marketed cloth as "glass cloth". The edges of the cloth are depressed into the marginal grooves, and then channel shaped metal cleats 12 are placed in these grooves and 100 upon the edges of the cloth to maintain the latter tightly in place. I would direct attention to the fact that the channel cleats are of a length less than the portions of the groove in which they are fitted. This is desired to space the ends of the channel from the drain ducts 5 to prevent covering of 105 these. These channels are held in place by turn buttons 13 pivotally mounted upon the bars of the frame in a position to swing over 110 and bridge the channels as shown in Figure 1.

From the foregoing description and drawing, it will be observed that I have evolved and produced a novel frame whereby a substantially transparent weather proof cloth may be stretched over it, and held tautly thereon. The arrangement of the grooves with the channels fitting tightly therein serves to stretch the cloth tightly when it is placed in position. That is, when the channels are forced down into the grooves, they have a tendency to exert a pull upon the cloth to stretch it. When the channels are properly in place they serve as wafer collecting troughs, and in rainy weather water which collects upon the cloth will be carried by the channels to the drain ducts to be disposed of. Under this arrangement the life of the cloth, and particularly the edges thereof will be prolonged. These and other advantages and features of the invention

have been made apparent from the description and drawings. Therefore, a more lengthy description is thought unnecessary.

While the preferred embodiment of the invention has been shown and described, it is to be understood that minor changes coming within the field of invention claimed may be resorted to if desired.

Having thus described the invention, what I claim as new and desire to secure by Letters Patent is:—

In a cloth frame wherein said frame is provided with a marginal groove formed at its corners with drain holes, and channel shaped retaining cleats fitted into the side and end portions of said groove terminating in spaced relation from said holes.

In testimony whereof I affix my signature.

LUCIUS A. BROWN.
